UNITED STATES PATENT OFFICE.

WILLIAM S. LUCKETT, OF EAST ORANGE, NEW JERSEY, AND MATTHIAS FOGDE, OF NEW YORK, N. Y., ASSIGNORS TO INTERNATIONAL CIGAR MACHINERY COMPANY, OF NEW YORK, N. Y., A CORPORATION OF NEW JERSEY.

WRAPPER-SMOOTHING MECHANISM FOR CIGAR-MACHINES.

No. 882,703.

Specification of Letters Patent. Patented March 24, 1908.

Application filed June 14, 1906. Serial No. 321,618.

To all whom it may concern:

Be it known that we, WILLIAM S. LUCKETT, a citizen of the United States, residing at East Orange, county of Essex, State of New Jersey, and MATTHIAS FOGDE, a subject of the Czar of Russia, residing in New York, county of Kings, and State of New York, have invented certain new and useful Improvements in Wrapper-Smoothing Mechanism for Cigar-
10 Machines, fully described and represented in the following specification and the accompanying drawings, forming a part of the same.

This invention relates to certain improvements in cigar smoothing devices, and has
15 for its object to produce a simple and effective smoothing device by which the wrapper may be smoothly and effectively laid upon and around the tip or head of a cigar.

With this and other objects not specifically
20 referred to in view, the invention consists in certain constructions and in certain parts, improvements and combinations such as will be hereinafter fully described and then specifically pointed out.

25 Referring to the drawings—Figure 1 represents in side elevation a form of smoothing mechanism embodying the invention. Fig. 2 is an end elevation of the construction shown in Fig. 1. Fig. 3 is a sectional plan 30 view of the construction shown in Fig. 1, and Fig. 4 is an end elevation of the mechanism, the cap which surrounds the smoothing mechanism appearing in section, the operating connecting rod appearing also in section, 35 and the main frame as it appears in Fig. 1 being removed.

In the concrete embodiment of the invention, the smoothing mechanism is represented as so constructed that it may form a part
40 of an organized cigar machine, such, for instance, as the machine shown in the application of Oluf Tyberg, filed June 10, 1905, Ser. No. 264,568.

The smoothing mechanism which forms
45 the subject of the invention includes two smoothing members which are arranged so that they operate at an angle to each other. The particular construction of these smoothing members may be varied within wide
50 limits. In the construction shown, these members consist of two brushes 1 and 2, the brush 1 being arranged to operate on lines parallel to the longitudinal axis of the cigar to be operated upon, and the brush 2 being

arranged to operate on lines cutting said axis. Furthermore, the best constructions will be of such a character as will enable a rotary movement to be effected between the cigar being operated upon and the smoothing members. In the construction selected for 60 illustration, this relative rotary movement is effected by rotating the brushes around the axis of the cigar as well as upon their own axes.

In the best constructions, also, these brushes will coöperate with an ironing device which also operates to smooth and polish the wrapper. While the construction of this ironing device may be widely varied, it may be generally similar to the device illustrated in the Tyberg application above referred to, that is to say, it may consist of a cup-shaped member 3 having an open side through one of the brushes, as 1, operates on the cigar. In the best constructions, and as shown, this cup shaped member will be mounted to rotate around the cigar. When this cup shaped member is mounted to rotate, the construction by which it is so mounted may be varied. As shown, it forms a part of a casting 4 which is clamped to a shaft 5. This shaft 5 is journaled in bearings 6 formed on uprights 7, these uprights being a part of a bracket which is mounted on the main frame indicated at 8 of the machine, the bracket being secured to this frame 8 by screws 9 or in any other suitable manner. This shaft 5 is, in the particular construction shown, driven by a bevel gear 10 meshing with a bevel gear 11 mounted on the vertical shaft 12 suitably supported in the bracket 7, the lower end of this shaft being provided with a gear 13 which is in turn driven by a gear 14 mounted on any suitable shaft of the machine with which the device is employed.

In order to enable the smoothing members to effect their function, a relative movement should be effected between the cigar and the members. In the particular construction illustrated, this is effected by rotating the 100 members around the cigar. While these movements may be accomplished by any suitable construction, as shown, the member 2 is mounted on a shaft 15 (see Fig. 4) this shaft being mounted in the casting 4 before 105 referred to. The shaft 15 is provided with a gear 16 which is in mesh with an intermediate 17 suitably mounted in the casting 4,

this intermediate 17 being in mesh with a stationary gear 18. This gear 18 is mounted on a hub 19 which is or may be formed on a head 20, this head being supported on the shaft 5 but being loose on said shaft. In the best constructions, also, as in the particular construction illustrated, these members will be given an operating movement in addition to their movement around the cigar, and when, as in the specific construction illustrated, these members consist of circular brushes, this movement will be a rotating movement.

In order that the member 1 may operate on lines parallel to the axis of the cigar, it is mounted on a shaft 21, this shaft being supported in bearings formed in the casting 4. This shaft is provided with a small bevel gear 22 in mesh with a similar gear 23, this gear being mounted on a shaft 24 which carries a gear 25 in mesh with the stationary gear 18 before referred to. As the shaft 5 and the casting 4 rotate, it will be readily understood that the members 1, 2, 3 are carried around the cigar, the position of which is indicated in dotted lines in Fig. 1, and at the same time the members 1, 2 will have movements on their own axes due to the traveling of the gears 17 and 25 on the stationary gear 18.

30 The smoothing devices may be arranged to be movable towards and from a suitable device for holding the cigar, such, for instance, as that shown in the Tyberg application before referred to. In the particular construction shown, the devices are made movable by causing the shaft 5 with the construction carried thereby to be movable lengthwise through the bearings 6. The gear 10 has a long hub 26 which prevents its moving with the shaft, this hub being connected to the shaft by a feather or spline in the ordinary way. The end of the shaft 5 is provided with a grooved collar 27 which is engaged by a lever 28 pivoted at 29 on the bracket which carries the uprights 7, this lever being operated by a connecting rod 30 and an operating lever 31 pivoted on any suitable part of the machine and operated in any suitable manner. In order to prevent 50 the head 20 from turning, two rods 32 may be provided, these rods extending through the rear of the head, and if desired, and as shown, into the gear 18 so as to firmly hold the head in the gear, these rods extending at 55 their rear ends into sockets formed in the bearing 6 which is nearest the head. The head may also be provided, as shown, with a casing 33 which may be removably secured to the head by means of a screw 34. This 60 casing will serve to protect the parts of the smoothing device and also will, in case there is paste on the outside of the cigar, prevent this from being spattered over the machine by the movement of the brushes.

65 While the smoothing mechanism which

has been described is particularly designed for use in connection with machines of the type disclosed in the Tyberg application referred to, it will be understood that constructions embodying the invention may be used in connection with machines widely different from that referred to. The invention is not, therefore, to be restricted to the specific construction hereinbefore described and illustrated in the accompanying drawings.

What is claimed is:

1. In a cigar smoothing mechanism, the combination with two members operating in planes at angles to each other, of means for effecting a relative rotary movement between the members and the cigar.
2. In a cigar smoothing mechanism, the combination with two members operating in planes at right angles to each other, of means for rotating the members around the cigar.
3. In a cigar smoothing mechanism, the combination with an ironing device, of two members operating in planes at an angle to each other, and means for effecting a relative rotary movement between said device and members and the cigar.
4. In a cigar smoothing mechanism, the combination with an ironing device, of two members operating in planes at an angle to each other, and means for rotating the ironing device and members around the cigar.
5. In a cigar smoothing mechanism, the combination with two members rotating in planes at right angles to each other, of means for effecting a relative rotary movement between the members and the cigar.
6. In a cigar smoothing mechanism, the combination with two members rotating in planes at an angle to each other, and means for rotating said members around the cigar.
7. In a cigar smoothing mechanism, the combination with an ironing device, of two members rotating in planes at an angle to each other, and means for effecting a relative rotating movement between the members and the cigar.
8. In a cigar smoothing mechanism, the combination with an ironing device, of two members rotating in planes at an angle to each other, and means for rotating the device and members around the cigar.
9. A cigar smoothing mechanism including two members operating in planes at an angle to each other and means whereby the tip of the cigar may be subjected to the action of said members.
10. In a cigar smoothing mechanism, the combination with an ironing device, of two members operating in planes at an angle to each other and means whereby the tip of the cigar may be subjected simultaneously to the operation of said members and ironing device.
11. In a cigar smoothing mechanism, the

combination with a cup shaped ironing device, of two brushes operating in planes at an angle to each other.

12. In a cigar smoothing mechanism, the combination with a cup shaped ironing device, of two brushes rotating in planes at an angle to each other.

13. In a cigar smoothing mechanism, the combination with a cup shaped member having an opening in its side, of two wrapper laying members operating in connection therewith, one of said members operating in the opening in the cup shaped member.

14. In a cigar smoothing mechanism, the combination with a cup shaped member having an opening in its side, of two brushes operating in connection therewith, one of said brushes operating in the opening in the cup-shaped member.

20 15. In a cigar smoothing mechanism, the combination with a cup-shaped member having an opening in its side, of a brush working through said opening, and a second brush operating on the cigar beyond said member and lying at an angle to the first brush.

16. In a cigar smoothing mechanism, the combination with a cup-shaped member having an opening in its side, of a rotating brush working through said opening, and a

second rotating brush operating on the cigar beyond this member and lying at an angle to the first brush.

17. In a cigar smoothing mechanism, the combination with two brushes arranged at an angle to each other, of means for rotating the brushes around their own axes and means for rotating the brushes around the axis of the cigar being operated on by the brushes.

35 18. In a cigar smoothing mechanism, the combination with a cup-shaped member having an opening in one side thereof, of a brush working in said opening, a second brush arranged at an angle to the first brush and working on the cigar beyond the cup-shaped member; means for rotating the brushes on their own axes, and means for rotating the brushes and the cup-shaped member around the cigar resting in the cup-shaped member.

40 In testimony whereof, we have hereunto set our hands, in the presence of two subscribing witnesses.

WILLIAM S. LUCKETT.
MATHIAS FOGDE.
